COIN HANDLING DEVICE

Charles A. Toce, Robert F. Broussard, and William N. Woodruff, Houston, Tex., assignors, by mesne assignments, to International Vehicular Parking, Ltd., Washington, D. C., a corporation of Delaware

Application August 14, 1937, Serial No. 159,100

7 Claims. (Cl. 194—1)

The invention relates to a device for receiving a coin and moving it into position to be received within a slot. The device may be used with different coin controlled mechanisms, a function of the present apparatus being to move the coin from an opening in the housing around to a position where it will drop within the coin receiving slot.

It is an object of the invention to provide a device of simple construction which will receive the coin introduced into the housing and move it to a position at right angles to its original position where it may drop into an opening provided to receive it.

15 The invention resides particularly in the construction and arrangement of the parts whereby the movement of the coin is easily and accurately performed.

Referring to the drawing herewith:

20 Fig. 1 is a rear view of the device embodying the invention.

Fig. 2 is a side elevation thereof.

Fig. 3 is a longitudinal section on the plane 3—3 of Fig. 1.

25 Fig. 4 is a view similar to the view shown in Fig. 2 but with the parts in a different position, and

Fig. 5 is a plan view of the device in the operating position shown in Fig. 1.

30 A mechanism constituting the invention is mounted upon a frame including a lower base plate 1, an upright front plate 2, and a rearwardly extending plate or housing 3. With reference particularly to Figs. 1 and 5 it will be noted that the housing 3 comprises two spaced plates, having between them a downwardly directed slot 4. This housing or coin receiving chamber thus constructed is mounted somewhat to one side of the center of the device. It has on its forward side a slot 5, through which the coin may be inserted. The slot or opening 5 is closed by a door 6 which is hinged at 7 adjacent its upper edge and is held in closed position by an arm 8 on its rearward side.

45 The arm 8 is a curved arm fixed at its upper end to a shaft 9. The lower free end of the arm 8 is curved forwardly to lie against the rearward side of the door 6. It is held resiliently in that position by means of a spring 10, which is secured to the screw 11, mounted on the arm and at its other end to the rearward wall 12 of the coin receiving housing.

50 As will be understood from Fig. 3, the coin may be introduced into the central chamber 3 on the housing and may drop downwardly

through the open lower end thereof. When it is thus dropped from the housing it is received within a swinging gate 13, which is provided with a vertical slot 14 to receive the coin. The gate 13 is normally held in a position away from the lower side of the coin receiving slot 14 and is moved into position to receive the coin by the action of the door 6.

The shaft 9 upon which the arm 8 is mounted has thereon at one side of the chamber 3 a bifurcated arm 15. This arm is moved by rotation of the shaft. It has at its outer ends a cross pin 16 which engages with a small block 17 upon a vertically positioned rod 18. The block 17 is slidable on the rod and is spaced from the upper end by means of a coiled spring 19, said spring bearing at its upper end against an adjustable nut 20 on the rod. The lower end of the rod is pivotally connected at 21 to an arm 22 of a bell crank lever.

The said bell crank lever is pivoted at 23 upon a bracket fixed on the framework. The lower arm 24 of the said lever has a pivotal connection at 25 with a link 26, the other end of which is connected at 27 to a short arm 28, projecting laterally from a sleeve or bushing 29.

The sleeve or bushing 29 forms the inner end of the coin receiving gate 13, previously mentioned. There is upon said sleeve 29 a laterally extending pin 30, to which a spring 31 is attached, the opposite end of said spring being secured at 32 to the frame of the housing. This spring tends to rotate the sleeve 29 of the gate 13 so as to swing the gate to coin discharging position illustrated in Fig. 1. In this position the end of the gate contacts with a stop arm 33 which is curved downwardly and secured to the lower portion of the frame.

There is a latch provided to latch the gate momentarily in coin receiving position. This latch is provided by a short pin 34 on the outer end of the gate 13. This pin is seen best in Fig. 5.

When the gate is swung from its discharging position shown in Fig. 5 around into coin receiving position below the slot 4 this pin 34 engages with a latching arm 35, shown in Fig. 1. Said latching arm has a shoulder 36 thereon to engage with said pin. Said arm tends to move upwardly into latching position due to the pressure thereon of spring 37, secured at 38 to the housing and bearing against the lower side of the latch.

The latch arm is held downwardly out of latching position by means of a slide arm 39, mounted on the side of the housing 3, as will

be understood from Figs. 2 and 4. Said arm has therein a slot 40 to receive a pin or post 41 and secured in the wall of the housing. The upper end of the slide arm engages the lower 5 side of the arm 15, which thus tends to move the arm 39 downwardly with the pin 41 in the upper end of the slot 40.

The lower end of the arm 39 has a shoulder shown at 42 in Fig. 4, said shoulder bearing 10 against the upper side of the latch arm 35, thus holding the latch arm in its lower position.

When a coin is inserted into the slot 5 it will push the door 6 upwardly into the dotted line position shown in Fig. 4. This will move the bifurcated arm 15 upwardly from the Fig. 2 position to the Fig. 4 position. As this releases the contact of the arm 15 with the upper end of the sliding arm 39 the pressure of spring 37 on the lower side of the latch arm 35 will be sufficient 20 to move the latch arm upwardly, thus pushing the slide arm 39 to its Fig. 4 position.

As the arm 15 is swung upwardly to the position shown in Fig. 4 it will move the bell crank lever and exert a thrust upon the link 26 to 25 swing the arm 28 and the gate from its position shown in Fig. 5 in the direction of the arrow inwardly beneath the slot 4. The coin is thereby enabled to drop from the slot 4 into the slot 13 in the gate. It will move downwardly in the 30 gate until the lower edge of the coin hits the arcuate margin 43 on the base plate 4. The contact with the base plate will prevent the coin dropping through the plate until it is swung to the Fig. 5 position where it will pass the edge of 35 the base plate and be allowed to drop downwardly out of the gate. It will be understood, therefore, that the function of the gate is to swing a coin from its position as inserted into the slot 4 to a position at right angles to its original 40 position and to then release it to drop out of the device.

It will be noted that the gate, when swung to coin receiving position, will be latched normally in that position due to the engagement of 45 the pin 34 with the latch shoulder 36. As soon as the coin drops downwardly out of the slot 4 it will allow the door 6 and the arm 8 to move back to their original position and when this is done the shaft 9 will be rotated to swing the 50 arm 15 thereon downwardly to the Fig. 2 position and thus move the slide arm 39 and by contact of the shoulder 42 thereon with the latch arm 35 the latch arm will be moved downwardly to free the door which will be swung to discharging 55 position by the action of the spring 31.

It will be seen that this coin handling mechanism may be in position entirely within a housing so that it will be protected from rain or snow. The door 6 will keep the rain and snow from entrance into the interior of the housing so as not to interfere with its proper action. The insertion of the coin itself will tend to move the coin receiving gate 13 to coin receiving position and the gate will be free to swing into discharging position as soon as the coin is in place therein. This operation is exceedingly simple and is not liable to get out of order. It provides a mechanism which cannot be easily tampered with from the outside. There is no way of withdrawing a coin after it has been once inserted and

received within the slot 14 in the gate 13. It is therefore simple and accurate in its operation and so constructed that it may not be tampered with in the operation of the device.

What is claimed is:

1. A coin handling device including a door to be moved by the insertion of a coin, a coin receiving chamber in which said door is movable, a gate vertically slotted to receive said coin below said chamber, means to retain said gate normally in coin discharging position, and means actuated by the swinging of said door by said coin to bring said gate into position to receive the coin from said chamber.

2. In a coin handling device, a narrow coin 15 receiving chamber having an entrance opening, a door held resiliently in position to close the entrance opening thereto, and means actuated by the movement of said door by a coin to receive said coin and swing it into coin discharging position at right angles to said chamber.

3. A coin handling device, a coin receiving chamber shaped to hold said coin in a vertical plane, a coin receiving opening in said chamber, a door closing said opening, a coin receiving 25 gate, means responsive to the movement of said door by a coin inserted into said chamber to move said gate below said chamber to receive said coin, and means to then move said gate to coin discharging position.

4. A vertically slotted chamber having a coin receiving opening, means to normally close said opening, means responsive to the movement of said closing means by a coin to move into co-operative position with said chamber to receive 35 said coin, and means to then move said coin receiving means away from coin receiving position to coin discharging position.

5. A coin receiving chamber open at its lower end to allow passage of a coin, a gate slotted to receive a coin, means movable in response to a coin inserted into said chamber to move said gate to position below said chamber to receive said coin, and a spring then acting to move said gate with said coin therein away from said chamber to a coin discharging position.

6. A coin receiving chamber open at its lower end to allow passage of a coin therefrom by gravity, coin receiving means, movable in response to the insertion of a coin into said chamber to a position below said chamber to receive said coin, means to latch said coin receiving means temporarily in position below said chamber, means to release said latching means when said coin has passed, and means to move said coin receiving means back to a coin discharging position.

7. A coin receiving chamber open at its lower end, a slotted coin receiving gate, a door closing an opening to said chamber, means responsive to the movement of said door when a coin is inserted into said chamber to swing said gate below said chamber to receive said coin, a latch to hold said gate momentarily in coin receiving position releasable when said coin has passed into said gate, and means to then swing said gate to a position away from said chamber.
